UNITED STATES PATENT OFFICE.

ALEXANDER RADÓ, MICHAEL MAYER, AND LUDWIG VON EGERHÁZY, OF BUDAPEST,
HUNGARY.

BUNG FOR CASKS.

Application filed November 30, 1921. Serial No. 519,018.

To all whom it may concern:

Be it known that we, ALEXANDER RADÓ, MICHAEL MAYER, and LUDWIG VON EGERHÁZY, all citizens of Hungary, residing at Budapest, in the Hungarian Republic, have invented new and useful Improvements in Bungs for Casks, of which the following is a specification.

This invention relates to bungs for casks. 10 It is well known that the ordinary manner of closing casks is unsatisfactory and is not secure against tampering with the contents of the cask.

Casks are mostly closed by means of a 15 wooden bung which, in being taken out, produces a deformation of the staves in such a manner that same have to be replaced almost every year.

These objections are obviated by the improved means hereinafter described and which are entirely safe and can be opened at any time, without damaging the cask.

The invention is shown by way of example in the accompanying drawings, in which:—

25 Figure 1 is a section partly in side elevation of the improved bung for closing the cask; Fig. 2 is a plan of same.

According to this invention, the bung hole of the stave *a* receives a metallic sleeve or socket *b* which is screwed into the wood. In this socket is mounted a metallic bung *d* having a groove at its lower portion for the reception of a packing ring *s*. The bung *d* carries locking bolts *g* which project diametrically into a circular groove formed in the inner side of the socket *b*, said bolts *g* being advanced and withdrawn by a suitable key *f*.

In order to close the bung hole, the bung *d* is introduced into the socket *b* and the key *f* is then turned so as to advance the bolts *g* into their locking position, thereby securing the real packing ring *s* in a liquid-tight position.

On the top surface of the bung *d* is secured 45 a cover-plate *i* turning on a peg *h* so that, after removal of the key *f*, said plate can be turned on the peg *h* in such a manner as to cover the key-hole and prevent dirt entering the key-hole. 50

The invention may readily take different forms of construction without exceeding the scope thereof. For example, the metallic socket *d* may have a smooth peripheral surface that is to say without screw-threads 55 and may then be held in position by any suitable means. Further, the locking bolts *g* and their locking mechanism may be such as to cause the packing ring *s* to be expanded thereby and thus increase the tightening 60 capacity of same.

We claim:—

1. A bung for casks comprising a metallic socket fixed in the stave of the cask, a circular groove formed in said socket, a 65 metallic bung inserted in the socket, locking bolts in the interior of the bung adapted to project into said circular groove and a key for operating the locking bolts.

2. A bung for casks comprising a metallic 70 socket fixed in the stave of the cask, a metallic bung loosely inserted in said socket, locking bolts connected with the bung, a circular groove formed in the bung near its lower end and a packing ring fitted in said 75 groove.

3. A bung for casks comprising a metallic socket fixed in the stave of the cask, a metallic bung inserted in said socket, means for tightening the bung, locking bolts connected with the bung, a key for operating said bolts, and a plate turning on a peg on 80 top of the bung for closing the key hole.
